SAWING MACHINE FOR BLOCK TRIMMING

Seward W. Mann, deceased, late of Pittsburgh,
Pa., by Beatrice A. Mann, administratrix, Pitts-
burgh, Pa.

Application September 24, 1946, Serial No. 698,913

1 Claim. (Cl. 144—2)

This invention relates to portable sawing machines, and more particularly to those that are suitable for resurfacing wooden blocks such as the cutting blocks that are used by butchers, leather workers, etc., the working surfaces of such blocks becoming unevenly worn or partly cut away during use, and therefore requiring that upper portions thereof be sawed away to provide another level working surface.

One object of the invention is to provide in apparatus of the character referred to, various parts that can readily be folded upon one another and other parts that can be easily removed, to facilitate transporting of the machine.

Another object of the invention is to provide a machine of the character referred to having an electric motor for driving a saw, the motor being mounted in an improved manner, for counterbalancing parts of the mechanism with respect to a supporting standard therefor and which can easily be adjusted to control the belt tension and which can conveniently be applied to and removed from the supporting framework.

In the accompanying drawings, Figure 1 shows the machine in side elevation; Fig. 2 is a plan view thereof; Fig. 3 is a plan view of the motor-supporting bracket of Fig. 1; Fig. 4 is a face view thereof; Fig. 5 is an edge view thereof; Fig. 6 is a sectional plan view, on an enlarged scale, of a portion of the apparatus of Fig. 2, and Fig. 7 is an enlarged sectional plan view of still another portion thereof.

The apparatus is here shown as used in sawing across the upper part of a butcher block, a portion of which is shown at 9, to give a level working surface to a worn block.

The apparatus comprises a frame having legs 10, 11 and 12. The upper ends of the legs 10 and 11 are connected to a tubular upright or post 13 by means of clips 14 and bolts 15. At their lower ends, these legs are connected to a headed stud 16 that is driven into the lower end of the tube 13, by means of bars 17 that have their outer ends welded to the legs and whose inner ends are flattened and have holes through which the stud 16 extends.

The leg 12 also is connected to the stud 16, by a bar 18. A bar 19 is rigidly connected to the upper end of the leg 12 and is connected by a bolt 20 to a wing member 21 that is welded to the upright 13. A brace 22 extends from the stud to the upper portion of the leg 12. When the bolt 20 is removed, the bars 18, 19 and 22, together with the leg 12, may be swung as a unit on the stud 16, to fold the leg 12 and the bars against one

of the legs 10—11, to facilitate transport or storing of the apparatus. Leveling screws 23 are provided for the legs.

Jointed arm members 25 and 26 are rotatably supported on the standard 13, they being pivotally connected to one another at 24. The arm 25 has bearing sleeves or collars 27 and 28 formed thereon and loosely fitting around the upright 13 so as to be rotatable about the axis of the upright and also being adjustable vertically thereon. A bearing collar 29 is clamped to the upright 13 and is held at vertically-adjusted positions thereon by a clamping bolt 30. This collar normally serves as a seat or vertical thrust bearing for the sleeve portion 28 of the swinging arm 25. A series of holes 31 or other suitable marking is provided on the upright 13 to serve as a scale for guidance in adjusting the collar 29, and hence the swinging frame, to desired heights, in accordance with the height of a block to be sawed. These holes may conveniently be spaced one-half inch or one-quarter inch apart, finer adjustments as to height being effected by turning the screws 23.

The outer end of the swinging arm 26 has a bearing 33 formed thereon for the shaft 34 of a saw 35 that is provided with a pulley 36. A shield 37 is connected to the arm 26 by bracket members 38 and 39, it being of somewhat larger diameter than the saw, so as to reduce danger of accidental contact with the saw.

A shaft that extends through the joint at 24 has secured thereto pulleys 41 and 42, the pulley 41 having driving connection with the pulley 36 by a belt 43. A belt 44 extends from the pulley 42 to a motor pulley 45. A water receptacle 46 is mounted on the arm 25 and has a hose connection 47 with a pipe 48 that extends through the shield and discharges water to the saw, thereby wetting the saw dust and preventing it scattering and blowing around. A valve 49 is provided for controlling flow of water through the pipe 48.

An electric motor 51 has a base 52 that is bolted to a bracket 53. The bracket has wings 54 that contain inclined notches 55 that are engageable with the end portions of a pin 56 that is supported in extensions 57 that project rearwardly from the lower portion of the arm 25. The motor can therefore be conveniently applied to and removed from the stand and can also be tiltably adjusted around the pin 56, as a pivot, as will be hereinafter explained.

The bracket 53 has an upstanding slotted arm 58 which is insertible upwardly into a yoke 59 that is carried by the upper portion of the arm 25. A screw 61 has threaded connection with the

yoke 59 and has formed thereon a shoulder 62. The inner end of the screw has a reduced portion 63 that will extend into the slot in the upper end of the arm 58 when the parts are in assembled position.

When the framework proper is in assembled position somewhat as shown in Fig. 1, the motor 51 can be placed thereon by lifting it until the bracket arm 58 projects upwardly through the yoke 59, whereupon inward and lowering movement of the motor will cause the bracket slots 55 to engage the pin 56 and thereby support the motor on the frame. The screw 51 at this time will have been retracted far enough relative to the yoke 59 to permit tilting of the motor clockwise so that the belt 44 can conveniently be applied to its pulleys 42 and 45. Thereupon, the screw 51 will be turned to move it inwardly on the yoke, with its reduced pointed end 63 entering the slot in the arm 58 and its shoulder 62 bearing against the outer face of said arm. The motor 51 will thereby be swung in a counterclockwise direction to give the required tension to the belt 41. When the parts are so assembled, the screw 51 will prevent accidental disengagement of the motor from the supporting pin 56.

The motor circuit is controlled by a switch 64 that controls the circuit of wiring at 65 and 66. A terminal block 67 on the arm 25 has a socket 68 to receive a plug from a house-lighting circuit or the like, to supply current to the wiring 65 and 66 and the motor 51.

A pin 70 is insertable through the bearing sleeve 27, when the swinging frame is fully raised on the upright 13. The arms 25-26, the motor 51 and their associated parts will thus be supported by the pin 70, on the upper end of the upright, while adjusting the collar 29 to the desired height. Removal of the pin 70 will then let the frame drop into position to be supported by the collar 29.

It will be seen that the saw frame can be moved into various positions with respect to the block 9. For example, the swinging arms 26 and 25 can be positioned alongside of the block. By reason of the swingable mounting of the arm 26 on the upright 13 and the pivotal connection of the arm 26 with the arm 25, the saw can be moved over a wide area, without the necessity of shifting the saw stand. Also, the arms 25 and 26 may be folded toward the plane of the legs 10 and 11.

as in the case of the leg 12 and its brace bars, for conveniently storing and transporting of the apparatus.

What is claimed is:

5 A sawing machine comprising a frame having a vertical post, a bearing sleeve carried by the post and rotatable thereon, about a vertical axis, a vertically-adjustable sleeve-supporting bearing on the post, a horizontally-extending arm carried by the sleeve, a circular saw journaled on the arm, a bracket carried by the sleeve in oppositely-extended relation to the said arm, and having tiltable movement thereon about a horizontal axis, adjacent to the lower end of the sleeve, an arm carried by the bracket and projecting therefrom in a direction transverse to said horizontal axis, a set screw having threaded engagement with an upper portion of the sleeve and engageable with said arm to adjust the bracket about its horizontal axis, a motor mounted on the bracket in counterbalancing relation to said arm and saw, the motor shaft being vertically disposed and having a pulley on its lower end, a driving connection between the pulley and the saw, and a retaining device engageable with an upper portion of the sleeve and movable into and out of position above the upper end of the post, for releasably supporting the sleeve on the upper end of the post while adjusting the sleeve-supporting bearing at a plane below the sleeve.

BEATRICE A. MANN,
Administratrix of the Estate of Seward W. Mann,
Deceased.
